DIRECT TRAVEL MECHANISM FOR ELECTRICAL REACTORS

Joseph Carnazza, Brooklyn, N.Y., assignor to JFD Electronics Corporation, Brooklyn, N.Y.
Filed May 24, 1965, Ser. No. 458,065
7 Claims. (Cl. 317—249)

This invention relates to variable electrical reactors in general and more specifically relates to a novel direct travel mechanism wherein movement of the adjustable reactor element is limited to translation as a result of rotating an adjusting element.

Direct travel mechanisms for electrical reactors are known to the art. One such mechanism is shown in co-pending application Serial No. 297,330, filed July 24, 1964 entitled "Guide Rod For Direct Travel Adjustment Mechanism" with M. A. Lafer and S. Levinson as co-inventors, and assigned to the assignee of the instant invention. Reactor components for high frequency electric circuits are usually, of necessity, constructed of elements which are positioned very close to one another. Slight changes in the spacing between elements will cause significant changes in reactances at high frequencies. Thus, it becomes necessary to assure that the elements of the reactor remain in adjusted position even under conditions of shock or vibration.

Further, it is desirable that the rate of reactance change be more or less uniform as the adjusting member is operated and for practical reasons it is necessary that the possibility of reversal be eliminated. That is, as the adjusting member is operated in a direction to increase reactance value this value should continuously increase without any decreases taking place, the converse being true for operation to decrease reactance.

It has been found advantageous to utilize a rotatable adjusting member, such as a screw having all but the top of its head enclosed, in that a relatively large angular movement produces a relatively small axial movement. However, it has been found that when the adjustable element of the reactor is permitted to rotate as it is being translated, any eccentricity between the adjustable element and its cooperating stationary element results in unpredictable variations in the rate of reactance change for a given rotation of the adjusting member. Hence, the necessity for limiting movement of the adjustable member to translational motion.

Accordingly, a primary object of this invention is to provide a novel operating means for translating without rotating an adjustable reactor element through rotation of an adjusting member.

Another object of this invention is to provide a novel direct travel mechanism for reactor elements that is relatively inexpensive.

Still another object of this invention is to provide a direct travel mechanism for trimmer or tuning capacitors which materially simplifies assembly.

A further object of this invention is to provide a novel direct travel mechanism for trimmer capacitors which provides good electrical contact between the bushing capacitor and a movable piston.

A still further object of this invention is to provide a novel direct travel mechanism for trimmer capacitors which provides adjustment holding torques and is free of backlash.

These as well as other objects of this invention will become readily apparent after reading the following description of the accompanying drawings in which:

FIGURE 1 is a longitudinal cross section of a trimmer capacitor constructed in accordance with the teachings of the instant invention.

2

FIGURES 2 and 3 are cross sections taken through lines 2—2 and 3—3, respectively, of FIGURE 1 looking in the directions of the respective arrows.

FIGURE 4 is an exploded perspective of the capacitor illustrated in FIGURE 1.

Now referring to the figures. Electrical reactor or capacitor 10 includes hollow glass cylinder 11 constituting a dielectric frame or form having conductive bands 12, 13 deposited on its outer surface at opposite ends thereof. Band 12 constitutes one terminal of the reactor to which electrical connections may be made while band 13 acts as a means for fixedly securing hollow bushing 14 to form 11. That is, bushing 14 is provided at a point intermediate the ends thereof with annular flange 15 dividing bushing 14 into an internal portion 16 and an external portion 17. Internal portion 16 is cylindrical and is disposed within form 11. Bushing shoulder 18, located at the junction between internal portion 16 and flange 15, concentrically positions the external surface of internal portion 16 in spaced relation with the interior surface of form 11. Solder bead 19, formed between conductive band 13 and flange 15, mechanically secures bushing 14 to dielectric form 11.

Cup shaped piston 20, constituting the adjustable element of reactor 10, is disposed within form 11 and is closely fitted with respect to the interior surface thereof. Piston 20 is so positioned that the skirt portion thereof telescopes over the internal portion 16 of bushing 14. Axially extending post 21 at one end of screw 22 extends through aperture 23 in the bottom of piston 20 with a solder connection between piston 20 and post 21 mechanically and electrically securing piston 20 to screw 22.

Screw 22 is provided with an exterior flattened portion 24 which extends axially from the part 21 to a point 24a just short of the end of the screw. With the body of screw 22 extending through D-shaped aperture 25 in washer 26, screw 22 may move axially with respect to washer 26 but is restricted against nuts 31, 32 for reasons which will hereinafter become obvious. Diametrically opposed radially extending ears 32a, 32a of nut 32 are disposed within the deep slots 34, 34 of rotatable bushing 35 while diametrically opposed radially extending ears 31a, 31a are entered into the relatively shallow slots 36, 36 of rotatable bushing 35. The end of bushing 35 is peened over at 35a to retain nut 31 mounted to rotatable bushing 35. Bushing 35 is provided with an axially extending cylindrical bore which is closely fitted to the exterior of screw 22 while the cylindrical exterior surface 35a of bushing 35 is closely fitted to the interior surface 50 of fixed bushing 14. Bowed spring washer 38, disposed within fixed bushing 14 and surrounding rotatable bushing 35, bears against interior shoulder 14a of bushing 14 and exterior shoulder 35b of bushing 35.

O-ring gasket 38', disposed within the annular groove 55 41 in surface 35a, acts as a seal between the stationary and movable bushing 14, 35. Groove 41 is located at the end of rotatable bushing 35 remote from the enlarged end 42 thereof containing slots 34 and 36. The end of bushing 35 remote from portion 42 is closed and is provided with slot 43 for receiving an adjusting tool such as a screwdriver.

The portion 17 of stationary bushing 14 disposed exteriorly of dielectric form 11 is provided with a threaded exterior surface to receive nut means for mechanically securing capacitor 10 to a mounting surface and also for making electrical connections to bushing 14.

In operation rotation of bushing 35 relative to bushing 14 is effective to rotate torque nuts 31, 32 relative to screw 22. Since screw 22 is maintained against rotation by virtue of its flat surface 24 cooperating with the flat boundary portion of aperture 25 in washer 26, screw 22

is limited to axial motion. This motion of screw 22 causes piston 20 to move along the axis of dielectric form 11 without any relative rotation between piston 20 and form 11.

Nuts 31, 32 in combination with spring 33 constitute a torque imparting means which prevents backlash and maintains a predetermined torque on screw 22 to prevent its accidental rotation with respect to rotatable bushing 35. Bowed spring washer 38 supplies a friction force which prevents accidental rotation of bushing 35 relatively to bushing 14. Thus, it is seen that the adjustable element 20 of electrical reactor 10 is caused to move axially without rotation whenever adjusting member 35 is rotated.

Although there has been described a preferred embodiment of this novel invention, many variations and modifications will now be apparent to those skilled in the art. Therefore, this invention is to be limited, not by the specific disclosure herein, but only by the appending claims.

The embodiments of the invention in which an exclusive privilege or property is claimed are defined as follows:

1. An electrical reactor including a support, an adjustable element, an adjusting member, first means mounting said member for rotation about an axis relative to said support, second means connecting said element to said member for axial movement relative to said support as said member is rotated about said axis while maintaining said element against rotation, said member including a tubular section, said element having a cup shape for telescoping over said tubular section, said second means including first and second cooperating sections in threaded engagement, said first section being rotated by said member, said second section being interposed between said first section and said element, said first means including a tubular bushing wherein said member is disposed, said member having a formation constructed and positioned for engagement by a tool for rotating said member, said formation disposed within the confines of said bushing, said member being tubular and being closed at a first end thereof, said formation being at said first end, a screw constituting said second section, a nut means constituting said first section mounted to said member at a second end thereof, said nut means including a first and a second nut mounted to said screw and spaced along the length thereof, a loaded spring means mounted to said screw, said spring means positioned between and bearing against said first and said second nuts, a bowed spring washer element surrounding said member and bearing against said member and said bushing.

2. An electrical reactor as set forth in claim 1 in which there is a sealing means interposed between the exterior of said member and the interior of said bushing.

3. An electrical reactor as set forth in claim 1 in which the support is tubular and surrounds the element, said

bushing having an interior part within said support with said element telescoped over said interior part.

4. An electrical reactor as set forth in claim 3 in which the bushing includes another part disposed outside the support and the first end of the member is surrounded by said another part.

5. An electrical reactor as set forth in claim 4 in which there is a sealing means interposed between the exterior of said member and the interior of said bushing.

6. An electrical reactor including a support, an adjustable element, an adjusting member, first means mounting said member for rotation about an axis relative to said support; second means connecting said element to said member for axial movement relative to said support as said member is rotated about said axis while maintaining said element against rotation, said member including a tubular section, said element having a cup shape for telescoping over said tubular section, said second means including first and second cooperating sections in threaded engagement, said first section being rotated by said member, said second section being interposed between said first section and said element, said first means including a tubular bushing wherein said member is disposed, said member having a formation constructed and positioned for engagement by a tool for rotating said member, said formation disposed within the confines of said bushing, said member being tubular and being closed at a first end thereof, a screw constituting said second section, a nut means constituting said first section mounted to said member at a second end thereof, said screw being provided with an axially extending flat surface coextensive with threaded portions of said screw, additional means mounted to said support and defining an aperture through which said screw is axially movable, said additional means having a straight section defining said aperture with a shape complementary to said flat surface, said straight section and said flat surface cooperating to prevent rotation of said screw.

7. An electrical reactor as set forth in claim 6 in which said nut means includes a first and a second nut mounted to said screw and spaced along the length thereof, a loaded spring means mounted to said screw, said spring means positioned between and bearing against said first and said second nuts.
